UNITED STATES PATENT OFFICE.

GILBERT W. BUTTLES, OF APPLETON, WISCONSIN.

MECHANISM FOR PRODUCING AN OSCILLATING MOVEMENT TO A SHAFT.

1,152,368.

Specification of Letters Patent. Patented Aug. 31, 1915.

Application filed October 7, 1914. Serial No. 365,426.

To all whom it may concern:

Be it known that I, GILBERT W. BUTTLES, a citizen of the United States, residing at Appleton, in the county of Outagamie and

5 State of Wisconsin, have invented a new and useful Mechanism for Producing an Oscillating Movement to a Shaft, of which the following is a specification.

My invention is designed for operating 10 washing machines in which the operating shaft of the mechanism which loosens the dirt and relieves the clothes of the dirt, has an oscillating movement, and the particular machine to which I have applied it having 15 been patented by George M. Millar, June 6, 1893, No. 499,136. It is adapted to be applied to any device in which a slow oscillating movement is required.

The invention is shown in the accompanying drawing in which,

Figure 1 is an end elevation of a washing machine having my improvement applied to it, with the washing machine shaft at one extreme limit of its oscillation. Fig. 2 is a 25 similar view of the washing machine with its shaft at the other limit of its oscillation. Fig. 3 is a side elevation of the washing machine with my improvement applied to it, the washing machine shaft being at an intermediate point in its oscillatory movement. Fig. 4 is an elevation, or plan of the 30 device by which the oscillatory movement is produced.

Similar numerals indicate like parts in the 35 several views.

One object of my invention is to produce an oscillatory movement which is not positive in its terminals, so that when a larger body of clothes is between the squeezing plates of the machine than the space for the 40 clothes is designed for, it will by reason of the resiliency of part of its mechanism, allow the revolutions of the revolving shafts of the mechanism without perceptibly interfering with the regularity of their revolutions or the power by which they are driven.

The device is adapted to be applied and is shown as applied to both hand and power operated machines, an electric motor and the necessary gearing being shown for reducing the speed to the desired rate for application in the most effective manner.

1, indicates a washing machine tub or enclosure; 2, its legs; 3, a lid hinged upon its 55 top; 2^a, a girt between the legs; 4, its oscillatory shaft; 5, crank arms, one at each end

of the shaft; 6, a bracket secured to the legs at one end of the inclosure by means of screws 7; mounted upon a pin 8, in said bracket is a wheel or pulley.

60

It should be observed that belt pulleys are shown in these drawings, but on account of the slow speed at which all of the shafts excepting that of the electric motor and its connecting counter shaft are driven, sprocket 65 wheels and chains will be more positive in their effect than belts and pulleys, and in this description will be considered as their equivalent. The wheel 9 is provided with an arm 10, having a pin 11, upon which a 70 small roller 12, is loosely mounted. A frame is mounted to oscillate upon the shaft 13 and is secured thereto, said shaft being journaled in boxes 13^a. The frame consists of a main bar 14, side pieces 15, secured to the 75 piece 14 with screws 16, and a bar 17, is suspended from the pin 18 and can swing a limited distance between the pieces 15, it having an arm 19, at right angles with it. The arm is provided with a right angled 80 bend 20 at its free end, from which bend a rod 21 extends to the bar 14. Mounted upon the rod 21, is a spring 22, and it may also have a spring 22^a.

The spring here shown is represented as a 85 rubber one, but a coiled wire one may be used if desired. Secured to the piece 17 with bolts 23, is a curved bar 24, between which and the bar 17, the roller 12, is arranged to revolve as the frame is oscillated 90 upon its shaft 13. At the lower end of the bar 14, an arm 25, extends outward below the spring 22, from which a connecting rod 26 extends to the crank arm 5 upon the side of the machine having the frame just described. Upon the opposite side of the machine an arm 27, similar to the arm 5, is secured to the shaft 13, and is connected by the rod 26 to the crank arm 5 upon that side. In Fig. 4, the main bar 14, is extended upward and is provided with a handle 28, by means of which the washing machine may be operated by hand power. In case the motive power fails during the progress of a washing, by disconnecting the pin 11, and the roller 12, the handle 28 can be used and the washing completed.

In the drawings a motor 29, is shown, which is supported upon the board 29^a. It is provided with a pulley 30, from which a 110 belt 31, is run to and around the large pulley 32 upon the shaft 33. From a small

pulley 34, upon the shaft 33, a belt 35, runs to and around a pulley 36, upon the shaft 37, which is journaled in boxes 37^a. A small pulley 38 upon the shaft 37, carries a belt 39, which runs to and around the pulley 9 upon the pin 8, of the bracket 6. The revolutions of the pulley 9, acts to swing the frame and through the connecting rods 26, to oscillate the shaft 4 of the machine. The shaft 37 is provided with a spline 40, and clutch member 41, the pulley 36 having integral with it the corresponding clutch member 42. A clutch operating lever 43, is mounted upon a bracket 44, secured to a leg 15 of the machine and is provided with a plate 45, secured to another leg, said plate having a notch 46, into which the lever is to be dropped for holding the clutch members in engagement. At the left end of the shaft 20 37, a beveled gear 47 is secured which is arranged to engage a companion gear upon a vertically arranged shaft 48, for operating a wringer, not shown, which may be secured upon the top of the machine inclosure 1. With the several shafts and pulleys shown, 25 the speed of the motor can be reduced to such a slow movement as will best effect the washing operation. It will be seen that by means of the springs 22 and 22^a, acting upon the bar 17, that an oscillating movement can be given to the shaft 4 of the machine that is not positive in its terminals, one that will permit its oscillation to change in extent as the bulk of the clothes within 30 the inclosure demand. It should also be noted that in consequence of the roller 12, being farther from the pivotal point of the bar 14 in a part of the revolutions of the wheel 9, that a longer movement is made of 35 the roller 12 in a part of the travel thereof

than in the other part, which alternating long and short movements is just what the washing mechanism demands for effective work.

Having described my invention, what I 45 claim and desire to secure by Letters Patent, is,—

A mechanism for imparting an oscillating movement to a shaft having a crank by which it may be revolved, in which a spring acts in limiting the terminals of its oscillations, consisting of a main bar having its point of oscillation near one end thereof, a second bar arranged parallel with and spaced from said main bar and pivotally connected with an arm thereof extending from its end opposite its pivotal end, an arm extending at right angles from the free end of said second bar having an angular termination, a spring arranged between the outer end of said angular terminal and the main bar, a third bar arranged outside of and parallel with said second named bar and spaced therefrom, in combination with a driven wheel mounted for revolution upon a suitable support and having an arm extending radially therefrom, a roller mounted for revolution upon the outer portion of said wheel arm between the second and third named bars, an arm extending at right 70 angles from the pivotal end of the main bar, and a connecting rod extending from the outer end of said main bar arm to a crank arm upon the aforesaid shaft to be oscillated.

GILBERT W. BUTTLES.
